UNITED STATES PATENT OFFICE.

FRANKLIN CHICHESTER, OF MILWAUKEE, WISCONSIN.

IMPROVEMENT IN SPRING ROCKING-CHAIRS.

Specification forming part of Letters Patent No. **142,145**, dated August 26, 1873; application filed June 14, 1873.

To all whom it may concern:

Be it known that I, FRANKLIN CHICHESTER, of the city and county of Milwaukee and State of Wisconsin, have invented a new and Improved Rocking-Chair; and I do hereby declare that the following is a full, clear, and exact description of the same, reference being had to the accompanying drawing forming a part of this specification.

This invention relates to the construction of that class of rocking-chairs which have stationary legs or stands, with which the seat is connected, by springs, which allow it to have a rocking motion; and consists in the peculiar mode of applying a plate-spring, as hereinafter described.

Figure 1 represents a side elevation of a spring rocking-chair constructed according to my invention. Fig. 2 is a top view.

A is the seat. B represents the plate-springs, one upon each side of the chair; C, a seat-pivot upon each side; D, a self-adjusting back; and E E, adjustable arms. F F represent the legs or stands of the chair. The plate-springs B are attached to the top of the stands, one end to the front of the seat at G and the other end to the rear at H, while it is attached at

the middle of the back D. The seat has projections I, which rest on the pivots C, which form points, upon which the seat rocks supported by the springs B. The points J J of the stand are stops to limit the rocking motion of the seat. The arms E are adjustable forward and back by means of the notched plates K on the seat, the pivoted bar L, and the sliding stop m, while the back D is pivoted to the other ends of the arms, as seen at N, and turns to adjust itself to the back of the person leaning against it.

These springs give the elastic support required, are easily applied, and may be manufactured at a reasonable price.

Having thus described my invention, what I claim as new, and desire to secure by Letters Patent, is—

The plate-springs B B, attached to the front of seat at G, to the rear at H, and to the middle of back D, in the manner and for the purpose described.

FRANKLIN CHICHESTER.
